[57] **CLAIM**

The ornamental design for a security waste disposal cabinet with pivotal door, as shown and described.

DESCRIPTION

FIG. 1 is a top and front perspective view of a security waste disposal cabinet with pivotal door showing our new design;

FIG. 2 is a rear elevation view thereof;

FIG. 3 is a top view thereof;

FIG. 4 is a right side elevation view thereof;

FIG. 5 is a front elevation view thereof;

FIG. 6 is a left side elevation view thereof;

FIG. 7 is a bottom plan view thereof;

FIG. 8 is a front perspective view thereof with the pivotal door in open condition;

FIG. 9 is a right side elevational view of FIG. 8, the left side elevational view being a mirror image of that shown;

FIG. 10 is a top plan view of FIG. 8;

FIG. 11 is a front elevational view of FIG. 8; and,

FIG. 12 is a bottom plan view of FIG. 8.
